UNITED STATES PATENT OFFICE.

RALPH DRABBLE, OF LONSDALE, RHODE ISLAND.

NOSING-MOTION FOR SELF-ACTING MULES.

SPECIFICATION forming part of Letters Patent No. 470,479, dated March 8, 1892.

Application filed July 20, 1891. Serial No. 400,148. (No model.)

To all whom it may concern:

Be it known that I, RALPH DRABBLE, a citizen of the United States, residing at Lonsdale, in the county of Providence and State of Rhode Island, have invented a new and useful Improvement in Nosing-Motions for Self-Acting Mules, of which the following is a specification.

My invention consists in an improved automatic mechanism for deflecting the winding chain to increase the velocity of the winding movement of the spindles, as hereinafter fully set forth.

Figure 1 represents a detail side view showing the quadrant-arm in its extreme elevated position. Fig. 2 represents the same side view with the quadrant-arm in its lower position, with the nose-peg in engagement with the chain. Fig. 3 represents the same side view showing the quadrant-arm in an intermediate position, with the stud at the end of the arm upon the faller-shaft in engagement with the pivoted engaging arm of the nosing-motion. Fig. 4 represents a detail top view of the nosing-motion.

In the accompanying drawings, A represents the quadrant-arm, to the upper end of which is attached the bracket B, and to the side of the said bracket at the point *a* is pivoted the nose-peg lever C, having at its forward end the nose-peg D, which at the downward movement of the quadrant-arm A engages with the winding-chain E. To the side of the bracket B is also pivoted the dog F, which engages with the serrated edge *b* of the nose-peg lever C and serves to hold the said lever in its adjusted position, the forward end of the lever C being actuated in an upward direction against the point of the dog F by means of the spring G, which is connected with the heel of the lever C at the point *e*. To the side of the downwardly-extending arm *f* of the bracket B is pivoted the engaging arm H, from the end of which jointed connection is made to the lever C by means of the link I, so that a downward pivotal movement imparted to the engaging arm H will be also imparted to the nose-peg lever C.

Upon the faller-shaft J is attached the back-

wardly-extending arm K, which is provided at its end with the stud L, adapted for engagement with the back of the pivoted arm H upon the forward movement of the carriage N, as shown in Fig. 3, whenever the thread has been first wound upon the cop *g* to its full diameter, and thereafter the continued engagement of the stud L of the arm K at each forward movement of the carriage N will, upon the gradually-increasing elevation of the winding position of the faller P and consequent decrease in the elevation of the arm K and stud L, cause the gradual drawing down of the nose-peg D to an increasing degree of engagement with the winding-chain E, the action of the stud L of the arm K upon the back of the engaging arm H being such as to cause the nose-peg lever to be slightly depressed at proper intervals, in which depressed position it is held by the dog F, the latter, during the downward movement of the nose-peg lever, having slid backward over one of the notches in the said lever, thus serving to move the winding-chain B more and more from a straight line, whereby an additional length of chain will be uncoiled from the winding on drum M, with a consequent increase in the velocity of the spindles for winding the thread upon the cop.

I claim as my invention—

1. The combination, with the quadrant-arm, the notched nose-peg lever, and the dog for holding the nose-peg lever in its adjusted position, of the pivoted engaging arm connected with the nose-peg lever, whereby upon the pivotal movement of the said arm the nose-peg lever will also be turned upon its pivot, substantially as described.

2. The combination, with the quadrant-arm, the notched nose-peg lever, the dog, and the pivoted engaging lever connected with the nose-peg lever, of the faller, the faller-shaft, the engaging arm upon the faller-shaft, the carriage, the winding-drum, and the chain, substantially as described.

RALPH DRABBLE.
